MACHINE FOR OPERATING UPON HIDES,
SKINS, AND LEATHER

Robert F. Whitney, Winchester, Mass., assignor
to The Turner Tanning Machinery Company,
Portland, Maine, a corporation of Maine

Application July 7, 1934, Serial No. 734,117

20 Claims. (Cl. 149—14)

This invention relates to machines for operating upon hides, skins and leather. While the invention is embodied in a machine for performing beaming or scudding operations upon skins 5 it is to be understood that the invention and various important features thereof may have other applications and uses.

This invention is an improvement upon the machine shown in United States Letters Patent 10 No. 1,658,506, granted February 7, 1928, upon an application filed in the names of J. A. Wheeler and R. F. Whitney. It is an object of the present invention to improve and simplify the embodiment of the invention disclosed in the patented machine and to provide a machine adapted 15 particularly for the handling of small pieces of work such as kid and calf skins.

To these ends and in accordance with an important feature of the invention there is provided 20 a work support upon which each piece of work in turn is clamped, during treatment, by a work clamping member arranged to be operated by the work support in such manner that as the work support moves toward work presenting position 25 with respect to a bladed cylinder the work clamping member is caused to approach the work support and finally to engage the work and clamp it firmly on the work support, the work support and work clamping member remaining stationary 30 in work presenting position during treatment of the work by said bladed cylinder. After the work support has moved a predetermined distance toward work receiving position away from the bladed cylinder, to insure that the work piece in 35 the machine is spaced from said bladed cylinder, the work clamping member is lifted promptly from engagement with the work so that the operator may remove the work early in the movement of the work support toward open position 40 and thus be enabled to introduce a fresh piece of work as soon as the work support and the work clamping member arrive at wide open work receiving position. Conveniently the work clamping member is pivoted to the work support 45 by cam members arranged to be guided by cam rolls carried by the frame of the machine.

Another important feature of the invention resides in an arrangement wherein a shaft, coaxial with a shaft supporting the bladed cylinder, is 50 provided with connections for operating a flexible work support or bolster to move the latter bodily toward and from the bladed cylinder so that pieces of work may be readily introduced when the bolster is in work receiving position and then 55 operated upon while the bolster is pressing the

work against the bladed cylinder. As shown, the bolster is carried at one end by the work support to which the work clamping member is pivoted and by which it is operated, in an organization wherein the work support, the bolster, and the 5 work clamping member are all operated in properly timed relation by connections with the single shaft located in coaxial relation to the shaft which carries the bladed cylinder. There is thus provided a simple, durable, and highly efficient 10 and compact construction for performing scudding or beaming operations upon pieces of work such as calf and goat skins.

These and other features of the invention and novel combinations of parts will now be described 15 in detail in the specification and then pointed out more particularly in the appended claims.

In the drawings,

Fig. 1 is a front elevation partly in section of a 20 beaming or scudding machine showing one embodiment of the invention;

Fig. 2 is an end view looking from the left in 25 Fig. 1, parts being broken away the more clearly to disclose the invention;

Fig. 3 is a section along the line III—III of 30 Fig. 1, looking in the direction of the arrows;

Fig. 4 is a view of the starting and stopping 35 mechanism of the machine;

Fig. 5 is a view along the line V—V of Fig. 4;

Fig. 6 is a view taken along the line VI—VI of 40 Fig. 4;

Fig. 7 is a sectional view along the line VII—VII of Fig. 4;

Fig. 8 is a view similar to Fig. 2 showing an 45 auxiliary work clamping means; and

Fig. 9 is a view similar to Fig. 8 showing the 50 work clamping parts in open work receiving position.

In the illustrated machine, which is specially 55 designed to perform beaming or scudding operations upon kid and calf skins, there is provided a bladed cylinder or drum 10, the blades 12 of which are disposed somewhat helically upon the surface of the cylinder and serve as both scudding and spreading blades while blades 14 are 40 disposed nearly or quite parallel to the axis of the drum and serve more as scraping blades. Preferably and as shown, the drum 10 is secured upon a hollow shaft or quill 16 mounted in bearings 17 in end members 18 (Fig. 2) of the machine frame. Secured to the quill 16 as by a spline 20 (Fig. 7) is a large gear wheel 22 arranged in mesh with a pinion 24 (Figs. 1 and 2) fixed to a counter shaft 26 which also carries a pulley 28 adapted to serve as the power pulley of 45 50 55

the machine. With power applied to the pulley 28 the bladed drum 10 will be continuously rotated as in practically all beamhouse machines.

In the illustrated construction, the skins are supported while being treated by a work support mechanism comprising a combined work support and work clamping member 30 carried at the upper ends of a pair of swing arms 32 pivotally mounted at their lower ends upon posts 33 constituting part of the end frames 18 of the machine. For operating the swing arms 32 about their pivots 33 there is provided a pair of pitmans 34 each having its front end pivoted at 36 to the upper end of the corresponding swing arm 32, and its rear end pivotally connected to a crank pin 38 (Figs. 2 and 7), said crank pin being carried by a crank arm rigid with a hub portion 40 of a cam wheel 42 splined at 44 to a shaft 46 that extends through and projects from the ends of the hollow shaft or quill 16. As shown most clearly in Fig. 7, the shaft 46 has end bearings at 48 within the quill 16, the said shaft 46 carrying at one end the hub portion 40 of the cam wheel 42, as stated above, and at its other end merely a crank arm (not shown) to operate a pitman like the pitman 34. As indicated in Figs. 2 and 7, each pitman 34 comprises a middle portion which is provided at its ends with right and left hand threads for adjustable engagement with similarly threaded socket carrying members 50 forming parts of the pitman so that the latter may be adjusted in length to facilitate proper positioning of the swing arms 32 in relation to the drum 10 and to an upper clamping member hereinafter described.

The work support mechanism mentioned above comprises also a flexible support or bolster 52 of a width coextensive with the length dimension of the drum 10, the purpose of the bolster 52 being to support a piece of work such as a skin 54 (Fig. 3) for the action of the blades 12, 14 on the drum 10. The flexible support or bolster 52 is attached at its lower end by means of a clamping bar 56 to a relatively heavy rod or pipe 58 (Fig. 3) rigidly clamped in the lower ends of two levers, one of which is shown at 60 (Figs. 1 and 2), each pivotally mounted at 62 on an end frame 18 of the machine. At its upper end the bolster 52 is disposed over the upper surface of the lower work clamping member 30 and is rigidly secured by bolts 66 to a front bar 67 of said lower work clamping member 30. Pivoted at 68 to each swing arm 32 is a link 70 which is slidable at its other end through an opening of suitable size in a box member 72 pivotally mounted at 74 upon an intermediate portion of the lever 60, a spring 76 being interposed between washers 78 on the link 70 and another washer 80 at the other end of the spring 76, the latter washer being backed by nuts 82 screw threaded on the link 70 to adjust the tension of the spring 76. At its free end the link 70 is screw threaded and provided with nuts 84 adapted to engage an extension 86 of the box 72, the arrangement being such that the levers 60 are swung forwardly as the swing arms 32 move forwardly to carry the bolster 52 to work receiving position, whereas, upon movement of the swing arms 32 in the reverse direction into the position shown in Fig. 2 the levers 60 are moved to carry the bolster 52 into position to press the work against the drum 10, yielding of the bolster 52 away from the drum 10 being permitted by the springs 76, thereby to

accommodate variations in the thickness of the work.

For co-operation with the lower work clamping member 30 there is provided an upper work clamping member 90, the said work clamping member being shown as an I-beam secured at its ends to a pair of cam members 92, each pivoted at 94 to the upper end of the adjacent swing arm 32. Each cam member 92 has a cam slot 96 for the reception of a cam roll 98 rigidly carried by a casting 100 adjustably secured by bolts 102 to the upper ends of the frame posts 33. The castings 100 may be readily adjusted by loosening the bolts 102 and by proper manipulation of adjusting screws or bolts 104. As shown in Fig. 1, the bolts 102 also pass through a frame cross bar 103 secured to the castings 100. It will be understood that upon movement of the swing arms 32 to the right in Fig. 2 the cam members 92 will be swung about the pivots 94 by the cam rolls 98 in the cam slots 96, the arrangement being such that the upper work clamping member 90 is swung upwardly to a wide-open position to facilitate removal of the work and insertion of a fresh piece of work. However, the clamp member 90 remains in clamping position during the first part of the outward movement of the swing arms 32, so as not to release the work until it has been moved away from the blades of the cylinder 10.

For operating the swing arms 32 through the pitmans 34 and the shaft 46, at the will of the operator, there is provided means for clutching the cam wheel 42 to the gear 22, it being recalled that cam wheel 42 is fastened to shaft 46 and the gear 22 is splined to the hollow shaft or quill 16. As shown most clearly in Figs. 4 and 7, the clutching means comprises an annular member 106 carried by a circular hub member 107, of the cam wheel 42, extending into an open cup portion of the gear wheel 22. Pivoted at 108 to the annular member 106 is a toggle link member 110 adjustable in length through having one constituent part screw threaded into another part, the toggle link 110 having a ball portion 112 arranged to engage in a socket 114 in the end of a link member 116 pivoted at 118 to the annular part of the cam wheel 42. Pivoted to the link member 116 is an arcuate clutch member 120 adapted to engage an inside cylindrical surface 122 of the cup portion of the gear wheel 22. Upon rotating the annular member 106 in a clockwise direction, in Fig. 4, the pivot 108 is moved with the member 106 to bring the center of the pivot in the dotted line in said Fig. 4, thus in effect straightening a toggle of which one portion is the toggle link member 110 and the other portion is a part of the annular member 106. By thus straightening the toggle the arcuate clutch members 120 are caused to engage the inner surface 122 of the gear wheel 22, thus clutching the wheel 42 to the gear wheel 22 which is power driven from the counter shaft 26. This movement of the annular member 106 in a clockwise direction is caused by a pair of relatively strong springs 122. For disconnecting the cam wheel 42 from the gear wheel 22 there is provided a stop member 124 having a wooden block 126 at its end to engage a corresponding wooden block 128 carried by an arm 130 projecting from annular member 106. When the stop member 124 is projected into the path of one of the arms 130 and engages the wooden block 128 therein the annular member 106 is turned in a counterclockwise direction, thus breaking the toggle and permitting a spring 132 to move the arcuate clutch mem- 75

ber 120 away from the clutching surface 122 on the gear wheel 22. It will be noted that the springs 122 serve also as buffers to soften the shock by which the cam wheel 42 and its connected parts are brought to rest. A pair of studs 133 on the annular member 106 project therefrom into position to engage opposite sides of a spoke 135 of the cam wheel 42 to prevent undesirable displacement of the annular member 106. Upon inspection of Figs. 1, 2, and 3 it will be observed that the stop member 124 is secured to a shaft 140 mounted in bearings carried by the machine frame and that at its forward end said shaft 140 carries an arm 142 adapted to be engaged by an arm 144 of a treadle lever 146 pivoted at 148 on the frame post 18, depression of the treadle 146 being resisted by a spring 150 one end of which is secured to a portion of the machine frame and the other end of which is attached to an arm 152 extending downwardly from the rear end of the shaft 140, the spring 150 having the function also of holding the stop member 124 yieldingly against the rim of the cam wheel 42 until a notch 154 in the rim is encountered by a roll 156 carried by the member 124.

If desired an additional work clamping member 160 (Figs. 8 and 9) may be provided to insure against displacement of the work. While the work clamping member 90 is amply sufficient to hold all the common grades of work during treatment thereof by the blades 12 and 14, the additional work clamping member 160 may be advantageously provided for larger and heavier pieces of work which are also unusually difficult to scud or to fine hair. As shown, the auxiliary work clamping member 160 is mounted upon levers 162 pivoted at 164 upon the cam members 92. Each lever 162 has a curved arm 166 extending over the top of the corresponding cam roll 98, said curved arm having a cam portion 168 for a purpose which will be hereinafter described. Connected to the end of the arm 166 is a spring 170 the other end of which is adjustably secured to an adjacent portion of the cam member 92. As shown most clearly in Fig. 9, the auxiliary clamping member 160 is provided with a concaved surface 172 for smoothly engaging the work and pressing it against a correspondingly convexed surface on the work support or lower clamping member 30.

It will be understood that the machine shown in Fig. 8 is at the same point in its cycle of operations as the machine shown in Fig. 2, that is, with the work clamping devices stationary in work clamping position. Following depression of the treadle 146 (Fig. 2) the crank pin 38 will move upwardly in the direction of the arrow (Fig. 2) with the result that the swing arms 32, work supporting member 30, and work clamping members 90 and 160 will be moved toward the right in Figs. 2 and 8. Since approximately the first half 173 of the lower wall of the cam slot 96 is concentric with respect to the axes of the pivot pins 35 of the swing arms 32, the work clamping member 90 will not be disturbed while the crank pin 38 is moving upwardly through an arc of about 45°, the reason for this being that the work should remain firmly that is, positively clamped to the work support 30 so long as any part of the work is still being contacted by the blades 12 and 14. At the point above mentioned, that is, when the crank pin 38 has moved through about 45°, the auxiliary work clamping member 160 starts to move upwardly, this being due to the fact that

the upwardly curved cam surface 168 on the arm 166 permits corresponding downward movement of the arm 166 under the action of the spring 170. By the time the crank pin 38 has traveled through an arc of 90°, both clamping members 90 and 160 have moved upwardly away from the work so that the operator may begin to withdraw the latter from the machine, the combined upward movement of the clamping members 90 and 160 as thus far described being due to a cam surface 174 on the lower wall of the cam slot 96. From then on each cam member 92 is swung about its pivot 94 due to the passing of said pivot 94 beyond a line connecting the axis of the cam roll 98 with the axis of the pivot 35 of the swing arm 32, the result being that what has theretofore been a forward movement of the cam members 92 (that is, in the direction of movement of the swing arms 32) is reversed with the result that the cam members 92 tip backwardly as shown in Fig. 9 during which there is a rearward movement of the cam slot 96 with respect to the cam roll 98. Fig. 9, it will be understood, shows the work clamping members 90 and 160 in fully open position in which they offer no obstruction to the introduction of a fresh piece of work. Upon again depressing the treadle 146, the work clamping members 90 and 160 and the work support 30 move in the reverse direction, that is, from the position shown in Fig. 9 to that shown in Fig. 8, with the result that the work is first clamped by the clamping member 90 and then by the auxiliary work clamping member 160. In both cases these work clamping members come down squarely upon the work so as not to be drawn thereover, since the latter might result in scuffing the work.

In operating the machine, a skin 54 is introduced into the machine when the upper work clamping member 90 (and 160, if present) and the swing arms 32 and the lower work supporting and work clamping member 30 are in open work receiving position (Fig. 9). The treadle 146 is then depressed whereupon the swing arms move to the positions shown in Figs. 2 and 8. During this movement of the swing arms the upper clamping member 90 (together with 160) moves downwardly to engage the work resting upon the upper surface of the lower work clamping and supporting member 30, the clamping of the work taking place before it is presented to the blades of the cylinder 10. Also the levers 60 are moved by the swing arms 32 to tension the flexible work supporting bolster 52 and bring it into work presenting relation with respect to the blades 12 and 14 on the drum 10, it being recalled that the drum 10 is continuously in rotation. After an interval, during which the blades operate upon the work, the operator again depresses the treadle 146 to cause the swing arms 32 to move to open position, the upper work clamping member 90 (and 160) moving upwardly to release the work only after the bolster 52 has been moved away from the blades of the cylinder 10 far enough to insure that the work will not be pulled into the machine by the rotating cylinder 10. This delay in the upward movement of the clamping member 90 (and 160) is due to the fact that the first half of the slot 92 is concentric with respect to the pivots 35 of the swing arms 32. The operator starts to remove the skin as soon as the latter is released at the beginning of the upward movement of the work clamping member 90 since it has to be reversed to secure treatment of the remaining portion of the skin. The other half,

i. e., the untreated portion of the work, is then introduced into the machine by throwing it over the lower clamping member 39 into position upon the flexible bolster 52 which has been moved away from the drum 10 into a work receiving position along with the swing arms 32 and lower clamping member 30. No attempt is made to straighten out the work except as that may be accomplished by stretching the work along the lengthwise dimension of the lower work clamping member 30, for the reason that, as the bolster approaches the drum, the blades of the latter in first contacting with the skin spread it out and then almost instantly operate to clean the surface of the skin of all hair, loose epithelial cells, and dirt. While the machine may be employed in unhairing operations upon light hides and skins, it is specially intended to perform the operations of fine hairing and beaming or scudding, that is, removing the fine hairs which persist after the usual unhairing operation and cleaning the surface of the skins from loose epithelial cells and hair follicles, and from the dirt which has remained after the liming and unhairing operations.

Having described my invention, what I claim as new and desire to secure by Letters Patent of the United States is:

1. In a machine for operating upon hides, skins and leather, a tool for treating the work, a work support movable between work receiving and work presenting positions with respect to said tool, said work support being stationary in its work presenting position while said tool is operating on a piece of work, a member for clamping the work on the work support just before the work is pressed against the tool, and co-operating cam members arranged to move the work clamping member to operative position as the work support moves to present the work to said tool, one of said cam members being stationary and the other movable with the work support during movement of the latter to work presenting position.

2. In a machine for operating upon hides, skins and leather, a rotary tool for treating the work, a work support having a pivotal mounting about which it is oscillated between work receiving and work presenting positions with respect to said tool, a member pivoted to the work support for clamping the work on the work support just before the work is pressed against the tool, said work support and work clamping member remaining stationary during treatment of the work by said tool, and co-operating cam members mounted on the work support and on the frame of the machine and operated by the work support during movement of the latter in one direction about its pivotal mounting to move the work clamping member positively to its operative or work clamping position.

3. In a machine for operating upon hides, skins and leather, a rotary tool for treating the work, a work support movable between work receiving and work presenting positions with respect to said tool, swing arms upon which said work support is mounted, a member pivoted to the swing arms for clamping the work on the work support just before the work is pressed against the tool, and co-operating cam members and cam rolls mounted on the work clamping member and on the frame of the machine and operated by the work support to move the work clamping member positively both toward and from the work support in timed relation to the movements of the work support.

4. In a machine for operating upon hides, skins and leather, a rotary tool, a hollow shaft to which said tool is secured, means for driving said shaft, a work support, a shaft mounted in said hollow shaft and arranged to operate the work support, work clamping means pivoted to the work support and arranged to be operated by the latter, and a clutch under the control of the operator for clutching the last recited shaft to said hollow shaft to effect movement of the work support toward and from said rotary tool.

5. In a machine for operating upon hides, skins and leather, a rotary tool for operating on the work, a work support movable between work receiving and work presenting positions with respect to said tool, a hollow shaft to which the rotary tool is securely fastened, power means for driving said shaft, means comprising a shaft mounted coaxially with respect to said hollow shaft and having connections to operate said work support, a work clamping member operated by the work support alternately to clamp the work on the support and to release the same, and means for clutching the last recited shaft to said hollow shaft whereby the work support may be moved toward and away from the rotary tool and the clamping member toward and away from the work support.

6. In a machine for operating upon hides, skins and leather, a rotary tool for treating the work, a work support movable between work receiving and work presenting positions with respect to said tool, a member for clamping the work on the work support just before the work is pressed against the rotary tool, cam members connected to said work clamping member and pivotally mounted upon the work support, and cam rolls mounted upon the frame of the machine for engagement with said cam members for positively operating the work clamping member both toward and from co-operative relation with respect to said work support as the latter moves between work receiving and work presenting positions.

7. In a machine for operating upon hides, skins and leather, a rotary tool, a hollow shaft to which said cylinder is secured, means comprising a gear wheel splined to said shaft for driving the latter, a work support, a shaft mounted in said hollow shaft and arranged to operate the work support, and a clutch under the control of the operator for clutching the last recited shaft to said gear wheel to effect movement of the work support toward and from said rotary tool.

8. In a machine for operating upon hides, skins and leather, a bladed cylinder for operating upon the work, a hollow shaft supporting said cylinder, a gear wheel splined to said shaft, a pinion to drive said gear wheel, a shaft mounted for rotation in said hollow shaft and having crank arms secured to its ends, pitmans connected to said crank arms, a pair of swing arms arranged to be operated by said pitmans, a work support carried by the swing arms, and means under the control of the operator to clutch the last-recited shaft to said gear wheel to effect movement of the swing arms and work support alternately toward and from the bladed cylinder.

9. In a machine for operating upon hides, skins and leather, a rotary tool for operating upon the work, a shaft to which said tool is secured, power means to drive said shaft, a bolster to support the work during treatment by said rotary tool, means connected to the ends of the bolster movably to support the latter, a shaft mounted axially with respect to the first-mentioned shaft for 75

5 rotation therewith and arranged to operate said bolster supporting means to move the bolster bodily with respect to the bladed cylinder, and means under the control of the operator to clutch the second-mentioned shaft to said power means to effect movement of the bolster alternately toward and from the bladed cylinder.

10. In a machine for operating upon hides, skins and leather, a rotary tool for operating on the work, a hollow shaft to which said tool is securely fastened, means for driving said shaft, a bolster to support the work during treatment thereof by the rotary tool, swing arms connected to opposite ends of the bolster movably to support the latter, a shaft mounted for rotation in said hollow shaft and arranged to operate said swing arms to move the bolster bodily with respect to the rotary tool, and a clutch under the control of the operator for operatively connecting the 15 last-recited shaft to said hollow shaft during rotation of the latter to cause movement of the bolster alternately toward and away from said rotary tool.

11. In a machine for operating upon hides, 20 skins and leather, a rotary tool, a hollow shaft journaled in the frame of the machine and to which said tool is securely fastened, means to drive said shaft, a work support, a bolster connected at one end to said work support, means for 25 movably supporting the other end of the bolster below said cylinder, a shaft journaled in said hollow shaft, means driven from the last-recited shaft to move the work support and bolster bodily toward and from the rotary tool, and a clutch 30 device under control of the operator for operatively connecting the last-recited shaft to said hollow shaft during rotation of the latter through 180° whereby said work support and bolster are moved alternately between work receiving and 35 work presenting positions with respect to the rotary tool.

12. In a machine for operating upon hides, 40 skins and leather, a rotary tool, a hollow shaft journaled in the frame of the machine and to which said tool is securely fastened, means to drive said shaft, a work support comprising a pair of swing arms, a bolster connected at one end to said work support, swing arms and a connecting bar for supporting the other end of the bolster below said cylinder, links connecting the work support swing arms to the bolster supporting swing arms, whereby the latter are operated by the former so that the bolster moves bodily between work receiving and work presenting relation to the rotary tool, a shaft journaled in said hollow shaft and arranged to operate said work support and bolster, and a clutch device under control of the operator for operatively connecting the last-recited shaft to said hollow shaft during 45 rotation of the latter through 180°.

13. In a machine for operating upon hides, 50 skins and leather, a rotary tool for operating on the work, a shaft mounted in the frame of the machine and arranged to have said tool fixedly secured thereto, means for driving said shaft, a work support movable toward and away from said rotary tool, a shaft mounted coaxially with respect to the first-mentioned shaft and arranged to move said work support yieldingly toward said 55 rotary tool, and means for clutching said shafts to each other for rotation of the second-mentioned shaft through 180° whereby the work support is moved alternately between work receiving and work presenting positions with respect to said 60 rotary tool.

14. In a machine for operating upon hides, 5 skins and leather, a bladed cylinder for operating on the work, a shaft mounted in the frame of the machine and arranged to have said cylinder fixedly secured thereto, means for driving said shaft, a work support comprising a bolster and a supporting device therefor movable toward and away from said cylinder, a shaft mounted coaxially with respect to the first-mentioned shaft, crank arms connected to the ends of the second-mentioned shaft, pitmans pivoted to said crank arms and to said bolster supporting device, and means for clutching said shafts to each other for rotation of the second-mentioned shaft through 10 180° whereby the bolster is bodily moved alternately between work receiving and work presenting positions with respect to said cylinder.

15. In a machine for operating upon hides, 15 skins and leather, a tool for operating on the work, a support for the work while it is being operated on by said tool, means for moving the work support toward and from said tool, a work clamping member movable toward and from the work support during movement of the latter toward and from said tool, means to cause the described movements of said work clamping member, and an auxiliary work clamping member mounted upon the first-mentioned work clamping member and arranged to be operated in 20 timed relation to the movements of said work support.

16. In a machine for operating upon hides, 25 skins and leather, a tool for operating on the work, a support for the work movable between work receiving and work presenting positions 30 with respect to said tool, a work clamping member pivotally mounted upon said work support, co-operating cam roll and cam-slotted members for operating the work clamping member during movements of said work support, and an auxiliary 35 work clamping member arranged to be operated by one of said cam roll and cam-slotted members to provide additional clamping effect 40 upon the work.

17. In a machine for operating upon hides, 45 skins and leather, a tool for operating on the work, a support for the work while it is being operated on by said tool, swing arms at the upper ends of which said work support is mounted, means for operating the swing arms to move the 50 work support between work receiving and work presenting positions with respect to said tool, a member mounted on the swing arms and operative to clamp the work upon said work support, an auxiliary work clamping member mounted on the first-mentioned work clamping member, and means for operating both work clamping members in timed relation to each other and to said work support.

18. In a machine for operating upon hides, 55 skins and leather, a tool for operating on the work, a support for the work movable between work receiving and work presenting positions 60 with respect to said tool, a work clamping member, members secured at each end of said work clamping member and pivotally mounted upon said work support, co-operating cam roll and cam-slotted members carried by the frame of the machine and by said pivoted members to 65 cause movements of the work clamping member in timed relation to movements of the work support, and an auxiliary work clamping member mounted on said pivoted members and arranged to be operated by one of said cam roll and cam- 70 75

- slotted members in timed relation to the movements of said work support.
19. In a machine for operating upon hides, skins and leather, a tool for operating on the work, a support for the work while it is being operated on by said tool, swing arms carrying said work support, means to operate the swing arms to move the work support alternately between work receiving and work presenting positions with respect to said tool, cam-slotted members pivotally connected to said swing arms, a work clamping member carried by said cam-slotted members, cam roll members mounted on the frame of the machine and arranged to co-operate with said cam-slotted members to operate the work clamping member in timed relation to the work support, and an auxiliary work clamping member arranged to be operated by one of said cam roll and cam-slotted members in timed relation to the movements of the work support.
20. In a machine for operating upon hides, skins and leather, a tool for operating on the work, a support for the work while it is being operated on by said tool, swing arms carrying said work support, means to operate the swing arms to move the work support alternately between work receiving and work presenting positions with respect to said tool, cam-slotted members pivotally connected to said swing arms, a work clamping member carried by said cam-slotted members, cam rolls mounted on the frame of the machine and arranged to co-operate with said slotted members to operate the work clamping member in timed relation to the work support, an auxiliary work clamping member pivotally mounted upon said cam-slotted members and arranged to be operated by said cam rolls in timed relation to the movements of said work support.
